UNITED STATES PATENT OFFICE.

WALTER J. BARRON, OF NEW YORK, N. Y., ASSIGNOR TO DENSMORE TYPEWRITER COMPANY, OF SYRACUSE, NEW YORK, A CORPORATION OF NEW YORK.

TYPE-WRITING MACHINE.

No. 893,971.

Specification of Letters Patent.

Patented July 21, 1908.

Application filed January 10, 1901. Serial No. 42,767.

To all whom it may concern:

Be it known that I, WALTER J. BARRON, citizen of the United States, and resident of the borough of Brooklyn, city of New York, 5 in the county of Kings and State of New York, have invented certain new and useful Improvements in Type-Writing Machines, of which the following is a specification.

This invention relates to tabulating mechanisms used upon typewriting machines, and more particularly to those in which any one of a series of denomination keys may be pressed both to project its associated carriage-stop and simultaneously release the 15 carriage.

Heretofore it has been necessary to hold the selected denomination key pressed in until the carriage has been arrested by the projected denomination stop. This has been 20 found objectionable, because where the carriage has a long run or jump to make, it requires pressure upon the denomination key for too great a length of time. If the key should be released before the carriage has 25 completed its run, the latter would come prematurely under the control of the letter feeding mechanism, and, if this were not noticed by the operator, the writing of the number would be commenced out of column, 30 or out of proper position.

Therefore one of the objects of my invention is to provide a mechanism which shall not require the pressure upon the key to be maintained until the coöperative members of 35 the carriage-arresting mechanism have come into engagement, so as thereby to enable the hands of the operator to be more quickly brought to a position over the writing keys for operation thereof after the carriage has 40 been arrested, and also to insure that when the key has once been pressed and the stop set and the carriage released, it will be impossible for the carriage to come to a halt at any point short of that predetermined by the 45 selected stop.

In carrying out my invention, I cause both the operated denomination stop and the carriage releasing device to become automatically locked in working position, so that, al- 50 though the operator may immediately release the key, the carriage may still complete its run and be arrested at the proper point. I further provide means for auto-

matically unlocking the denomination stop and its connected mechanism, including the 55 carriage releasing device.

My invention consists broadly in the combination with a series of denomination stops of a series of latches; and it further consists in the various features of construction and 60 combinations of devices hereinafter described and particularly pointed out in the appended claims.

In the accompanying drawings, Figure 1 is a sectional elevation taken longitudinally 65 of a No. 6 Remington typewriter machine having a Gorin tabulator attached thereto and showing my improvements, the several parts being in normal position. Fig. 2 is a sectional perspective view of a group of 70 latches and their appurtenances. Fig. 3 is a view similar to Fig. 1, but showing a denomination key and connected parts in working position. Fig. 4 is a rear sectional elevation of a carriage escapement wheel and a novel 75 detent therefor. Fig. 5 is a plan of the machine.

In the several views, certain parts are omitted or broken away, and similar parts are designated by similar numerals of reference. 80

From a base 1 rise corner posts 2, which sustain a top plat 3, upon which are supported type bars 4, the latter being connected by rods 5 to horizontal levers 6, pivoted in rear upon a common fulcrum bar 7 and having at their forward ends keys 8. A transverse universal bar 9 beneath the levers is hung by rods 10 upon branches 11 of a vibratory frame which is pivoted at 12 upon a fixed bracket 13. Said frame comprises an 85 upright arm 14, upon the upper end of which are mounted a stepping dog 15 and a detent dog 16. Said universal bar is normally held up against the key levers by a dog-rocker spring 17. In engagement with the stepping dog 15 is an escapement wheel 18, which is suitably connected to a pinion 19 in mesh with a releasable rack 20, the latter being attached to the front ends of arms 21 hinged at 22 to a carriage 23, to which is connected a platen frame 24. Upon the carriage 23 is supported, by means of rearwardly extending arms 25, a rack 26, upon which may be arranged any number of suitable column stops 27. 95

A set of denomination stops 28 is arranged 100

105

in rear of the column stop rack, and suitably supported upon the upper part of a frame 29, which may be attached to the rear end of the machine base in any suitable manner, as by 5 screws 30. Each of the denomination stops is of plate-like or blade-like formation, and by means of a horizontal slot 31 works upon horizontal cross bars 32 fixed in the frame 29. Normally the blades stand a little in rear of 10 the column stop rack, and are movable forwardly upon the rods 32 so as to project into the path of the column stops. Each blade carries a lug 33 for engaging a bar 34 of a bail or U-frame, the arms whereof are designated 15 as 35 and are pivoted at their lower ends at 36 upon the frame 29. One of said arms is extended at right angles forwardly from the pivot 36, as at 37, and is connected by an upwardly extending link 38 to the rear end of a 20 carriage-release lever 39, which is pivoted at 40 upon a bracket 41 fixed upon the top plate, and extends thence forwardly beneath the carriage rack 20 so that it may lift the latter out of mesh with the pinion 19. 25 The denomination stops are operated by means of a set of vertical levers 42 of the first order, which are individually pivoted at 43 upon the frame 29 and are connected at their lower ends by horizontal push rods 44 30 to a set of denomination keys 45, the latter having returning springs 46.

The devices specifically described above are well-known.

Pivoted at 47 upon the upper arms of the 35 upright levers 42, is a set of forwardly extending latches or locks 48, whose noses normally rest upon a catch bar 49, which is formed integrally with a pair of upwardly extending supporting arms 50, the latter being 40 sustained in any suitable manner, as by forwardly extending threaded wires 51, which are tapped into the top plate at 52, and which may also serve as attaching devices for the upper end of frame 29. A 45 coiled spring 53 (Fig. 2) may be strung over the forward portions of the latches and caught upon screws 54 tapped into the arms 50 so as to hold or snap the latches down. These latches are designed to catch over the 50 upper forward edge of the catch bar 49, so as to detain their respective levers 42 and their appurtenances in working position. In order that said guard bar may be adjusted closely, I tap into it a horizontal screw 55, the rear 55 end of which bears against the frame 29, so that when said screw is turned in one direction or the other, the said guard is pressed away from or permitted to spring towards said frame by reason of the resiliency of the 60 arms 50; a lock-nut 56 being provided for preserving the adjustment.

A universal latch-release bar 57 is arranged horizontally at a point forward of the catch bar 49 and just below the noses of the latches, 65 said release bar being fixed upon the rear

end of an arm 58, which projects rearwardly from the dog rocker 14, to which latter it is secured by a screw 59.

In operation, any denomination key 45 may be pressed rearwardly, to cause a projection of its associated denomination blade 28, the movement of the key being communicated to the blade through the rod 44 and lever 42. The lug 33 upon the moving blade engages the universal bar or bail 34, and pushes the latter forwardly about the axis 36, and through the bail arm 37, link 38 and lever 39 lifts the rack 20 out of mesh with the pinion, thus permitting the carriage to be driven by its spring in the usual drum 62 80 until the column stop 27 engages said projected denomination blade, whereby the carriage is arrested at the proper point to begin the writing of a number whose denomination corresponds to the operated key 45. During 85 the described stop-projecting movement of the lever 42, its latch 48 is carried forwardly so as to catch over the bar 49, and thereby detain or lock in working position said lever and its associated stop, the rack 20 being 90 consequently supported out of mesh with the pinion 19, whereby premature reengagement of the rack with the pinion is prevented. It will be understood that when the run or jump of the carriage is completed, all of the 95 parts, inclusive of the denomination stop, latch and rack 20, remain in the described abnormal positions. After the carriage has thus been positioned by the tabulating devices, the desired number may be written by 100 manipulation of the type keys 8, whose movements are communicated by the levers 6 and links 5 to the type bars 4, each of said levers also operating the universal bar 9, whereby the dog rocker 14 is caused to reciprocate, and the dogs 15 and 16 to coöperate with the escapement wheel 18 to permit a 105 step-by-step movement of the paper carriage.

It will be understood that the arm 58 and release bar 57 vibrate in unison with the dog rocker, and hence at the first depression of any type key, said arm and release bar are swung upwardly, and the latter engages the nose of the latch which has been described as having caught over the bar 49, and lifts 110 said latch out of engagement with said bar, whereupon the latch, the lever 42, the stop 28, the rod 44 and the key 45 are all returned to normal position by the reaction of spring 46, the bail 34 being permitted to return to 115 normal position, and the rack 20 dropping as 120 normal into mesh with the pinion 19.

The described release of the latch 48 and consequent re-connection of the carriage to its letter-feeding devices occur when the key 125 has made about half of its printing stroke, as illustrated by dotted lines at Fig. 3, so that by the time said stroke is completed and the first type impression is made, the carriage is again completely under the control of the 130

letter-feeding mechanism. Preferably the parts should be so constructed and arranged as that at the tabulating operation the carriage may be arrested just before it reaches the exact point at which the first type impression is to be made so that there may be a drop of say one-hundredth of an inch or less after the disengagement of the denomination stop from the column stop and before the type reaches the platen, this drop being desirable in order to secure a slight clearance for the rack 20, so that it may drop freely into mesh with the pinion. It is further desirable that the pinion be at this time in the precise rotative position necessary for receiving the rack, so that the points of the rack teeth may not land upon the points of the pinion teeth; and to this end I support upon the carriage-release lever 39 a 20 detent 60, said detent being formed upon the end of a bent arm 61, which is riveted to the lever. Normally said detent stands away from said wheel, as illustrated at Fig. 1; but at the disengagement of the rack 20 from the pinion 19, said detent is swung about the lever axis 40 into engagement with the escapement wheel, so as to prevent back-lash thereof, whereby the rotative position of the pinion is preserved, and hence the rack teeth register with the pinion notches when the carriage is subsequently arrested by the cooperation of the column stop and denomination stop. The rack is thus enabled to re-engage properly with the pinion, and liability of a spurious letter-feeding movement of the carriage at this time is avoided. Thus it will be seen that when the operator pushes the denomination key, the denomination stop is positioned and the feed rack 20 is disengaged from the pinion 19; also that both of said devices are automatically or mechanically locked in their abnormal positions, so that the carriage is enabled to complete its run independently of continued pressure upon the key 45 by the operator, who may therefore immediately withdraw his finger, and prepare to write. Moreover, it will be observed that the subsequent return of the denomination stop and the rack 20 to normal position is accomplished automatically, or without attention from the operator.

It will be seen that the letter-feeding mechanism for the carriage comprises two separable members 19 and 20, which may be separated by the same key that projects a denomination stop 28, thereby permitting the carriage to run until arrested by engagement of the column locating stop thereon with the projected denomination stop. The projected stop is held in abnormal or working position mechanically by its latch or detent 48, which also serves mechanically to detain the carriage-releasing device 39 in abnormal position, thus maintaining the disengagement of the separated letter-feed-

ing members 19 and 20, so that by merely pressing any key of the denomination-determining mechanism the correct movement of the carriage is insured. The latches 48 have a connection, through the dog rocker 14, to the type-operating keys 8, so that after one of said latches is set in working position, it may be moved out of working position by any type-operating key, or by the space-key, thereby automatically freeing from the control of said latch both the stop and its key, as well as the carriage-releasing device 39.

Various changes may be made in details of construction and arrangements of parts within the scope of the invention. The denomination keys may be in other form than sliding push keys, as well known in the art.

What I claim^{as} new and desire to secure by Letters Patent, is:

1. In a typewriting machine, the combination of a power driven carriage, letter spacing mechanism, a column stop, a set of denominational stops, key actuated means adapted to move said denominational stops to their respective operative positions, means operative by said key actuated means to release the carriage from the control of the letter spacing mechanism, and means to keep the carriage from control of the letter spacing mechanism when pressure is removed from the operated key before the carriage is arrested by the tabulating stops.

2. In a typewriting machine, the combination of a power driven carriage, letter spacing mechanism, a column stop, a set of denominational stops, a set of keys adapted to move said denominational stops to their respective operative positions, means operative by each of said keys to release the carriage from the control of the letter spacing mechanism, and means to keep the carriage from control of the letter spacing mechanism when pressure is removed from the operated key before the carriage is arrested by the tabulating stops.

3. In a typewriting machine, the combination of a power driven carriage, letter spacing mechanism, a column stop, a set of separately movable denominational stops, a set of keys each adapted to move one of said denominational stops to its operative position, means operative by each of said keys to release the carriage from the control of the letter spacing mechanism, and means to keep the carriage from control of the letter spacing mechanism when pressure is removed from the operated key before the carriage is arrested by the tabulating stops.

4. In a typewriting machine, the combination of a power driven carriage, letter spacing mechanism, a column stop, a set of denominational stops, key actuated means adapted to move said denominational stops to their respective operative positions, means

operative by said key actuated means to release the carriage from the control of the letter spacing mechanism, and means to keep the selected denominational stop in its operative position and to keep the carriage from control of the letter spacing mechanism when pressure is removed from the operated key before the carriage is arrested by the tabulating stops.

10 5. In a typewriting machine, the combination of a power driven carriage, letter spacing mechanism, a column stop, a set of denominational stops, a set of keys adapted to move said denominational stops to their
15 respective operative positions, means operative by each of said keys to release the carriage from the control of the letter spacing mechanism, and means to keep the selected denominational stop in its operative position
20 and to keep the carriage from control of the letter spacing mechanism when pressure is removed from the operated key before the carriage is arrested by the tabulating stops.

6. In a typewriting machine, the combination of a power driven carriage, letter spacing mechanism, a column stop, a set of separately movable denominational stops, a set of keys each adapted to move one of said denominational stops to its operative position, 25 means operative by each of said keys to release the carriage from the control of the letter spacing mechanism, and means to keep the selected denominational stop in its operative position and to keep the carriage from 30 control of the letter spacing mechanism when pressure is removed from the operated key before the carriage is arrested by the tabulating stops. 35

rating stops.

7. In a typewriting machine, the combination of a power driven carriage, letter spacing mechanism, a column stop mounted on the carriage, a set of denominational stops mounted on the frame of the machine, key actuated means adapted to move said denominational stops to their respective operative positions, means operative by said key actuated means to release the carriage from the control of the letter spacing mechanism, and means to keep the carriage from control of the letter spacing mechanism when pressure is removed from the operated key before the carriage is arrested by the tabulating stops.

8. In a typewriting machine, the combination of a power driven carriage, letter spacing mechanism, a column stop mounted on the carriage, a set of denominational stops mounted on the frame of the machine, a set of keys adapted to move said denominational stops to their respective operative positions, means operative by each of said keys to release the carriage from the control of the letter spacing mechanism, and means to keep the carriage from control of the letter spacing mechanism when pressure is removed.

from the operated key before the carriage is arrested by the tabulating stops.

9. In a typewriting machine, the combination of a power driven carriage, letter spacing mechanism, a column stop mounted on the carriage, a set of separately movable denominational stops mounted on the frame of the machine, a set of keys each adapted to move one of said denominational stops to its operative position, means operative by each of said keys to release the carriage from the control of the letter spacing mechanism, and means to keep the carriage from control of the letter spacing mechanism when pressure is removed from the operated key before the carriage is arrested by the tabulating stops.

10. In a typewriting machine, the combination of a power driven carriage, letter spacing mechanism, a column stop mounted on the carriage, a set of denominational stops mounted on the frame of the machine, key actuated means adapted to move said denominational stops to their respective operative positions, means operative by said key actuated means to release the carriage from the control of the letter spacing mechanism, and means to keep the selected denominational stop in its operative position and to keep the carriage from control of the letter spacing mechanism when pressure is removed from the operated key before the carriage is arrested by the tabulating stops. 95

11. In a typewriting machine, the combination of a power driven carriage, letter spacing mechanism, a column stop mounted on the carriage, a set of denominational stops mounted on the frame of the machine, a set of keys adapted to move said denominational stops to their respective operative positions, means operative by each of said keys to release the carriage from the control of the letter spacing mechanism, and means to keep the selected denominational stop in its operative position and to keep the carriage from control of the letter spacing mechanism when pressure is removed from the operated key before the carriage is arrested by the tabulating stops. 100 105 110

12. In a typewriting machine, the combination of a power driven carriage, letter spacing mechanism, a column stop mounted on the carriage, a set of separately movable denominational stops mounted on the frame of the machine, a set of keys each adapted to move one of said denominational stops to its operative position, means operative by each of said keys to release the carriage from the control of the letter spacing mechanism, and means to keep the selected denominational stop in its operative position and to keep the carriage from control of the letter spacing mechanism when pressure is removed from the operated key before the carriage is arrested by the tabulating stops. 115 120 125

13. In a typewriting machine, the combi- 130

nation of a power driven carriage, letter spacing mechanism, denomination-determining mechanism including tabulating stops and a set of stop-actuating keys, means operative by each of said keys to release the carriage from the control of the letter spacing mechanism, and means to keep the carriage from the control of the letter spacing mechanism when pressure is removed from the operated key before the carriage is arrested by the tabulating stops.

14. In a typewriting machine, the combination of a power driven carriage, letter spacing mechanism, denomination-determining mechanism including tabulating stops and a set of stop-actuating keys, means operative by each of said keys to release the carriage from the control of the letter spacing mechanism, and means to keep the key actuated tabulating stop in its operative position and to keep the carriage from control of the letter spacing mechanism when pressure is removed from the operated key before the carriage is arrested by the tabulating stops.

15. In a typewriting machine, the combination of a power driven carriage, letter spacing mechanism, a column stop, a set of separately movable denominational stops, a carriage releasing device, means for mechanically detaining said carriage releasing device in working position, and means for automatically freeing said carriage releasing device from the control of its detaining means.

16. In a typewriting machine, the combination of a power driven carriage, letter spacing mechanism, a column stop, a set of separately movable denominational stops, key actuated means adapted to move said denominational stops to their respective operative positions, a carriage releasing device movable to working position by said key actuated means, means for mechanically holding both the selected denominational stop and said carriage releasing device in their working positions, and means for automatically freeing them from the control of the holding means.

17. In a typewriting machine, the combination of a power driven carriage, letter spacing mechanism, denomination-determining mechanism including tabulating stops and a set of stop-actuating keys, means operative by each of said keys to release the carriage from the control of the letter spacing mechanism, means to keep the key-actuated tabulating stop in its operative position, and to keep the carriage from the control of the letter spacing mechanism when pressure is removed from the operated key before the carriage is arrested by the tabulating stops, and means for automatically restoring the key-actuated tabulating stop to its normal position and the carriage to the control of the letter spacing mechanism.

18. In a typewriting machine, the combination of a set of type-operating keys, a power driven carriage, letter spacing mechanism, a column stop, a set of separately movable denominational stops, a carriage releasing device, means for mechanically detaining said carriage releasing device in working position, and means actuated by the type operating keys for freeing the carriage releasing device from the control of its detaining means.

19. In a typewriting machine, the combination of a set of type-operating keys, a power driven carriage, letter spacing mechanism, a column stop, a set of separately movable denominational stops, key actuated means adapted to move said denominational stops to their respective operative positions, a carriage releasing device movable to working position by said key-actuated means, means for mechanically holding both the selected denominational stop and said carriage releasing device in their working positions, and means actuated by the type-operating keys for freeing the selected denominational stop and carriage releasing device from the control of the holding means.

20. In a typewriting machine, the combination of a set of type-operating keys, a power driven carriage, letter spacing mechanism, denomination-determining mechanism including tabulating stops and a set of stop-actuating keys, means operative by each of said stop-actuating keys to release the carriage from the control of the letter spacing mechanism, means to keep the key-actuated tabulating stop in its operative position and to keep the carriage from the control of the letter spacing mechanism when pressure is removed from the operated tabulating key before the carriage is arrested by the tabulating stops, and means controlled by the type-operating keys for restoring the key-actuated tabulating stop to its normal position and the carriage to the control of the letter spacing mechanism.

21. In a typewriting machine, the combination of a power driven carriage, letter spacing mechanism, carriage releasing means, variable spacing mechanism including a set of separately movable stops, means for moving said stops and for operating the carriage releasing means, and means separate from said releasing means for controlling the last named means and for holding the actuated stop in an operative position until the carriage is arrested.

22. In a typewriting machine, the combination of a power driven carriage, letter spacing mechanism, carriage releasing means, variable-spacing mechanism including a set of separately movable push keys, each adapted to operate the carriage releasing means, means for holding the push keys temporarily in the positions to which they are forced

- when they are actuated, and means for releasing the push keys after the variable spacing mechanism has performed its duty.
23. In a typewriting machine, the combination of a paper carriage, letter spacing mechanism, a stop, a set of key-actuated denominational stops coöperative with the first mentioned stop, said denominational stops being separately movable, carriage releasing means controlled by the action of any of said denominational stops, means for locking the denominational stops in their working positions, and means for unlocking said denominational stops.
- 15 24. In a typewriting machine, the combination of a paper carriage, character keys, letter spacing mechanism, tabulating mechanism, including a set of denominational keys, for releasing the carriage and arresting it at 20 different denominational positions, the operation of any single denominational key of the set being effective to release the carriage and to determine at which of the denominational positions the carriage will be arrested, and 25 means for locking some of the key-actuated parts of the tabulating mechanism in their working positions.
25. In a typewriting machine, the combination of a paper carriage, character keys, 30 letter spacing mechanism, tabulating mechanism including a set of denominational keys for releasing the carriage and arresting it at different denominational positions, the operation of any single denominational key of the 35 set being effective to release the carriage and to determine at which of the denominational positions the carriage will be arrested, means for locking some of the key-actuated parts of the tabulating mechanism in their working 40 positions, and means controlled by the character keys for releasing said parts.
26. In a typewriting and tabulating mechanism, the combination of a power-driven carriage, letter-feeding devices therefor, a 45 carriage-releasing device, a column-stop, a set of independently movable denomination stops, and means for mechanically holding said denomination stops and said carriage-releasing device in abnormal position.
- 50 27. In a typewriting and tabulating mechanism, the combination of a power-driven carriage, letter-feeding devices therefor, a column stop, a set of independently movable denomination stops, a set of locking devices 55 connected to said denomination stops, and a carriage-releasing device which may be controlled by any of said locking devices.
28. In a typewriting and tabulating mechanism, the combination of a power-driven 60 carriage, letter-feeding devices therefor, a column-stop, a set of independently movable denomination stops, means for locking said stops in working position, and a carriage-releasing device called into action at the 65 movement of any of said denomination stops and held in abnormal position by said stop-locking means.
29. In a typewriting and tabulating mechanism, the combination of a power-driven carriage, letter-feeding devices therefor, a 70 column-stop, a set of independently movable denomination stops, a set of locking devices one for each of said denomination stops, and a carriage-releasing device called into action at the movement of any of said denomination 75 stops and controlled by said locking devices.
30. In a typewriting and tabulating mechanism, the combination of a power-driven carriage, letter-feeding devices therefor, a column-stop, a set of denomination stops, a 80 set of independently movable keys for adjusting said denomination stops, a carriage-releasing device operable by any of said keys, and means also operable by said keys for holding in abnormal position both said carriage-releasing device and said denomination 85 stops.
31. In a typewriting and tabulating mechanism, the combination of a power-driven carriage, escapement devices therefor, a column stop, a set of independently movable denomination stops, a set of independently 90 movable keys connected to said denomination stops, a carriage-releasing device operable by any of said keys, a set of latches for holding in abnormal position said denomination stops, said keys and said carriage-releasing device, and means for automatically unlocking said latches.
32. In a typewriting and tabulating mechanism, the combination of a set of type-operating keys, a power-driven carriage, key-controlled escapement devices for said carriage, a column stop, a set of independently 95 movable denomination stops, a set of independently movable keys connected to said denomination stops, a carriage-releasing device operable by any of said keys, a set of latches for holding in abnormal position said denomination stops, said denomination keys 100 and said carriage-releasing device, and means controlled by said type-operating keys for releasing said latches.
33. In a typewriting and tabulating mechanism, the combination of a power-driven 105 carriage, a column stop, a set of denomination stops, a set of key-operated levers connected to said denomination stops, latches 110 pivoted upon said levers, a set of type-operating keys, a vibratory carriage-escape- 115 ment device operated by all of said type keys, a release bar 120 57 carried by said vibratory device, and a carriage-releasing device 39 controlled by said denomination-stop levers.
34. In a typewriting and tabulating mechanism, the combination of a set of type-operating keys, a power-driven carriage, key-controlled escapement devices therefor, including dog rocker 14, a column-stop rack 125 upon said carriage, a set of denomination 130 stops

stops mounted upon the framework of the machine, latches 48 connected to said denomination stops, catch bar 49, release bar 57 carried by said dog rocker, and carriage-releasing lever 39 connected to said latches.

35. In a typewriting and tabulating mechanism, the combination of type-bars 4 having keys 8, a power-driven carriage having rack 20, escapement-dog rocker 14 operated by said keys, column-stop rack 26 upon said carriage, denomination stops 28 upon the framework, connections between said rack 20 and said denomination stops, levers 42, spring-pressed latches 48, catch bar 49, release bar 57 operated by said dog rocker, rods 44, keys 45, and springs 46.

36. In a typewriting and tabulating mechanism, the combination of a series of type-operating keys, a power-driven carriage, an escapement wheel therefor, a releasing device for said carriage, a column stop, a denomination stop, means for mechanically holding said releasing device in operative position, means controlled by the type keys for freeing said carriage-releasing device from its holding means, and a detent as 60 moved by said carriage-releasing device into engagement with said escapement wheel.

37. A typewriter attachment having a series of auxiliary keys for disengaging the paper carriage from the step by step feeding devices, a lock separate from and independent of the carriage disengaging means for locking the parts in this position and a series of movable stops for arresting the carriage at varying distances from predetermined points.

38. A typewriter attachment having a series of auxiliary keys for disengaging the paper carriage from the control of the step by step feeding devices, a lock separate from and independent of the carriage disengaging means for locking the carriage in this position, a series of stops for arresting the carriage at varying distances from a predetermined point, and devices for automatically unlocking the locking devices.

39. In a typewriting machine and tabulating mechanism, the combination of a carriage, character keys, a series of denominational stops, a coöperative stop, a key for each denominational stop, carriage releasing means controlled by said denominational keys, automatically actuated means for locking the parts controlled by said denominational keys in the abnormal positions, and means for automatically releasing said locking means at a subsequent operation of any character key.

40. In a typewriting machine and tabulating mechanism, the combination of a carriage, a feed rack carried thereby, a feed pinion with which said rack meshes, a tabulating stop carried by the carriage, independently operable tabulating keys, a set of

denominational stops each controlled by one of said tabulating keys, means controlled by each of said tabulating keys for disengaging the rack from its pinion, means for automatically locking the feed rack and denominational stops in the positions to which they are moved by said keys, and means for automatically releasing said locking means.

41. A typewriter having devices for taking the paper carriage from the control of the step-by-step feeding devices and putting it in control of a variable spacing mechanism, push keys independent of the type keys and spacing bar for controlling said devices, including provisions whereby said push keys remain at rest in the moved position during a variable feed movement and means for automatically returning said push keys to normal position when the variable feed movement has been completed.

42. In a typewriting and tabulating mechanism, the combination of a power driven carriage, letter feeding devices therefor, a carriage releasing device, a column stop and a set of independently movable denomination stops, with means for holding said carriage releasing device in abnormal position, the said construction including provisions whereby the devices for controlling said denomination stops remain at rest during the period the said carriage releasing device is held.

43. In a typewriting and tabulating mechanism, the combination of a power driven carriage, letter feeding devices therefor, a column stop, a set of independently movable denomination stops, means for releasing the carriage from the letter feeding devices called into action at the time of the movement of any of the denomination stops, devices for holding said carriage releasing means in abnormal position during the feed movement permitted by said stops.

44. In a typewriting and tabulating machine, the combination of a power driven carriage, a letter feeding device therefor, a column stop, a set of movable denomination stops, means for actuating said denomination stops, a carriage releasing device called into action by the actuating means of said denomination stops, locking means for said carriage releasing device, said construction including provisions whereby the actuating means for said denomination stops remain at rest during the period that the carriage releasing device is locked.

45. In a typewriting machine, the combination of a power-driven carriage, letter spacing mechanism, carriage releasing means, a set of auxiliary keys for operating the carriage releasing means, a lock separate from the carriage releasing means, for locking a part of the last mentioned means in working position, and a set of dogs movable by said

auxiliary keys, for arresting the carriage at varying distances from predetermined points.

46. In a typewriting machine, the combination of a power-driven carriage, letter spacing mechanism, carriage releasing means, a set of auxiliary keys for operating the carriage releasing means, a lock separate from the carriage releasing means for locking a part of the last mentioned means in working position, a set of dogs, movable by said auxiliary keys, for arresting the carriage at varying distances from predetermined points, and means for automatically restoring the carriage to the control of the letter spacing mechanism.

47. In a typewriting machine, the combination of a power-driven carriage, letter spacing mechanism, carriage releasing means, variable spacing mechanism including a set of separately movable stops, for arresting the carriage at different predetermined points, means for moving said stops into their working positions, means separate from the carriage releasing means for keeping the carriage from the control of the letter spacing mechanism until the carriage is arrested by said stops, and means for automatically re-

storing the carriage to the control of the letter spacing mechanism after the carriage is arrested.

48. In a typewriter having devices for taking the paper carriage from the step-by-step feeding devices and putting it in control of variable spacing devices, push keys independent of the type keys and spacing key for operating these transfer devices, means for holding said transfer devices in their operated positions during the variable feed movement, the construction including provisions whereby the push keys are kept temporarily in the positions to which they are forced when they are actuated, and means for returning the push keys to their normal positions after the completion of the variable feed movement.

Signed at the borough of Manhattan, city of New York, in the county of New York, and State of New York, this ninth day of January A. D. 1901.

WALTER J. BARRON.
